(57) **CLAIM**

The ornamental design for a pencil sharpener, as shown and described.

DESCRIPTION

FIG. 1 is a perspective view of a pencil sharpener showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is another perspective view thereof, showing the pencil sharpener in a separated state.

A portion of the cord of the pencil sharpener is shown with a symbolic break in its length. The appearance of any portion of the article between the dot-dash break lines forms no part of the claimed design.
